UNITED STATES PATENT OFFICE.

GEORGES MARCONNET, OF PARIS, FRANCE.

APPARATUS FOR PRODUCING GAS.

No. 851,954.

Specification of Letters Patent.

Patented April 30, 1907.

Application filed January 30, 1905. Serial No. 243,364.

To all whom it may concern:

Be it known that I, GEORGES MARCONNET, a citizen of the Republic of France, residing at Paris, Republic of France, have invented 5 Improved Apparatus for Producing Gas from Pulverizable Fuel, of which the following is a specification.

In gas producers ordinarily employed it is difficult to succeed in burning fuel containing either a sufficiently large quantity of volatile matters, or fuel whose combustion produces an undue quantity of adhesive clinkers. This difficulty arises from the fact that the fuel to be burned is delivered into the producer in heaps, at regular intervals often wide apart. The parts of which this charge of fuel is composed are first of all conductively heated, at the same time distillation commences in the freshest parts or layers and simultaneous combustion in the hottest parts or layers. The presence of these parts or layers in contact at a high temperature, causes the vitrifiable portions to become so to speak welded together or to adhere to the neighboring walls of the producer and they ultimately, unless removed, choke up the apparatus. Moreover as this combustion takes place in a somewhat restricted area, and at a constantly decreasing temperature, the result is that the hydrocarbons are not decomposed. Again, it is not possible with this method of combustion to deal with entirely pulverulent fuel capable of existence in the most coherent form, even if as fine as the finest flour, without the necessity of continually stirring the fuel heaps to prevent caking, or to fill up the pockets which form.

Another difficulty, that obtains in motive power installations having gas motors and 40 gas generators, consists in the fact that the gas motor very often has to produce a variable power and the gas producer often contains a considerable quantity of carbon (coal). The result therefore is that the motor of variable power will be supplied with gas resulting from the more or less vigorous combustion of a constant quantity of fuel, without regard to the power developed by the motor.

50 In order that the composition of the gas produced may be constant, it is necessary that the gas generator should be capable in a given time of burning a quantity of fuel exactly in relation to the power of the motor at a given moment and to burn it under the

same conditions of chemical reaction whatever this power may be.

This invention relates to an apparatus which allows of this combustion being made complete and possible whatever the fuel may contain, in volatile products, cinders, adhesive clinkers and above all when the fuel is in the form of very fine dust, and to proceed in such a manner that at any given instant only the exact quantity of coal necessary and sufficient for producing the gas necessary for the power of the motor at that instant shall be burned; the residues of the combustion, cinders and clinker, being automatically deposited at a part where they are no longer hurtful and whence they can be easily removed.

Figures 1 and 2 of the accompanying drawing show respectively in longitudinal vertical section and in horizontal section on the line A, 75 A of Fig. 1 one construction of apparatus according to this invention.

First and foremost the fuel, if it is not already in a pulverulent state, is reduced as by grinding to as fine a powder as may be desired. In this form it is deposited in a hopper *a*, in sufficient quantity for any desired length of time. The bottom of this hopper is provided with a distributing device which allows the powdered fuel to flow in the form 85 of a sheet of spray or rain, so to speak, into a vertical conduit *b*.

The feed of the distribution mechanism is so regulated that the quantity of powdered fuel falling is greater than that which is necessary for the producer to supply sufficient gas to the motor at its maximum power. As before stated the fuel falls into the vertical conduit *b*, and the resistance which the air admitted by a branch conduit *g* opposes to its fall has the effect of so separating its particles, that at a point *c* in the conduit *b* it appears as a cloud of falling coal dust. From the point *c* a feed conduit *r* branches off which at its other end opens into a vertically arranged 100 fall tube *e*. This tube *e* is constructed of refractory earth such as fire clay and may be of any form, but preferably that of an elongated rectangular oblong as shown. The two side walls *h* and *k* of the fall tube *e* form 105 in conjunction with outer walls 1 and 2 jackets or conduits *o* and *p*, which are likewise constructed of refractory earth. The inner walls *h* and *k* are each pierced with small holes 3 placing the jackets or conduits *o* and 110

p in communication with the conduit or fall tube *e*.

The jacket or conduit *o* is in communication by a pipe *x* with a source of poor or rich 5 gas under a slight excess of pressure while the jacket or conduit *p* communicates with the outer air by a pipe *y*.

The gas issues by the small holes 3 over the whole height of the wall *k*, and, if a light be 10 put to one of the orifices, the whole column of orifices takes fire. The wall *k* of the fall tube *e* thereupon becomes transformed into a veritable gas grill.

The base of the fall tube *e* opens into a 15 lower chamber *q*, constructed of refractory earth, of somewhat large volume and which is itself connected by a conduit *z* to a gas purifier and to the motor A shown diagrammatically in Fig. 1.

20 The motor being at rest, there falls by the action of the distribution mechanism of the hopper *a*, a cloud of coal dust past the orifice *c* of the conduit *b*. When the motor has remained at rest only for one hour or for two 25 hours, it is not necessary to light the gas again as it is lighted of itself on coming in contact with the sides *h* and *k* which are still red; if the stop is of longer duration, these sides will be less hot and therefore it must be 30 lighted again. Under these conditions, if one or two turns be given to the motor by appropriate means it will draw in at *g* a certain quantity of air; this air will enter the gas producer by the orifice *c* drawing in with 35 it a quantity of coal dust in proportion to the speed with which the air passes through the said orifice. This mixture of air and coal dust as it falls in the tube *e* comes in contact with the burners therein in succession. The 40 coal first begins to distil and then burns as fast as it falls, but, at the same time, a certain quantity of air will be caused to pass through the orifices 3 pierced over the whole height of the opposite inner wall *h*, and this 45 air will contribute to complete combustion. It follows therefore that on its arrival at the bottom of the fall tube *e* all the fuel admitted to the tube *e* has been burned.

50 In consequence of the air and gas which pass through the walls *h* and *k* and stream from the orifices 3 thereof, the coal dust, gases, products of the distillation and combustion of the latter, as also the cinders which result therefrom cannot touch these 55 walls.

To burn the carbon so as to have only 60 oxid of carbon, it is necessary to conveniently proportion the quantities of air and coal admitted to the gas producer. For 65 this purpose there is placed at the base of the hopper *a* a small inclined plate *d* the inclination of which can be adjusted, so that the coal dust falls at any required distance from the front of the orifice *c*. This orifice 65 is itself provided with a flap *m* controlled

in any suitable manner, or it might be a cock *l*, which allows the speed of the air passing through the orifice to be augmented or diminished at will. Finally by means of a cock *u* the entrance of air admitted to the 70 jacket or conduit *p* between the walls 1 and 2 can be regulated.

The combustible gases thus produced pass, conjointly with the residues of combustion, into the chamber *q*, whence they 75 proceed to the motor, after having passed through a suitable cooler and purifier, the cinders remaining in the chamber *q*.

A branch 4 is led from the conduit *z* supplying the motor to a small exhauster *v* by 80 means of which the gas necessary to feed the burners is drawn into the burner feed pipe *x*. The ignition is effected by any suitable gas supply or by carbureted air.

It will be seen that with this arrangement 85 of apparatus, the more power the motor absorbs, the greater is the quantity of air and coal dust drawn in at the orifice *c*; the quantity of coal burned is therefore proportional to the energy absorbed. If, on the 90 contrary, the motor runs on a vacuum, and consequently requires but very little gas, the coal in powder continues to fall regularly and uniformly down the tube *b* and onto the overflow heap *j*, whence it is taken 95 to be returned to the hopper *a*, either by hand, or by a bucket chain elevator or by any other means.

If the motor has to work with a feeble charge of gas, for a comparatively long 100 time, several days for example, the movement of the falling coal is regulated in proportion to this charge.

The gas producer proper is placed in a second jacket 5. The space between this latter and the gas producer is filled with heat insulating material so that the jackets or conduits *p* and *o* may be protected against cooling.

110 The insulator of the heat can be any non-conductor of heat, preferably fossil meal ("farine fossil, kieselguhr") or asbestos.

A tube *t* passing from the fall tube *e* and through the jacket 5 to the outside of the producer is closed at its outer end by a transparent plate of mica *n*, or the like, a slight hole being thus formed which permits of following the combustion in the gas producer.

What I claim is:

1. In an apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, means whereby powdered fuel is caused to pass in a continuous shower more or less closely in front of said inlet orifice and means that 120

draw regulated quantities of air and powdered fuel through said inlet orifice to said gas producer, substantially as described.

2. In apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, means for adjusting the area of said inlet orifice, means whereby powdered fuel is caused to pass in a continuous shower more or less closely in front of said inlet orifice and means that draw regulated quantities of air and powdered fuel through said inlet orifice to said gas producer, substantially as described.
- 10 15

3. In apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, a second conduit communicating with the inlet orifice of said feed conduit, and with the atmosphere, distributing means whereby powdered fuel is caused to pass in a continuous shower through said second conduit and more or less closely in front of the inlet orifice of said feed conduit and means that draw regulated quantities of air and powdered fuel through said inlet orifice to said gas producer, substantially as described.
- 20 25 30

- 35 4. In apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, a vertically arranged conduit communicating with the inlet orifice of said feed conduit, a pipe supplying air to said vertical conduit, a powdered fuel hopper at the upper end of said vertical conduit, distributing means for causing fuel from said hopper to fall in a continuous shower through said vertically arranged conduit and more or less closely in front of the inlet orifice of said feed conduit and means that draw regulated quantities of air and powdered fuel through said inlet orifice to said gas producer, substantially as described.
- 40 45 50

- 55 5. In apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, an adjustable plate controlling the area of said inlet orifice, a vertically arranged conduit communicating with the inlet orifice of said feed conduit, a pipe supplying air to said vertical conduit, a powdered fuel hopper at the up-

per end of said vertical conduit, distributing means for causing fuel from said hopper to fall in a continuous shower through said vertically arranged conduit and more or less closely in front of the inlet orifice of said feed conduit and means that draw regulated quantities of air and powdered fuel through said inlet orifice to said gas producer, substantially as described.

6. In apparatus for the production of combustible gas from pulverulent fuel, a gas producer comprising a long vertically arranged combustion chamber throughout the length of which jets of flame extend, a conduit adapted to feed fuel and air to said gas producer and having an inlet orifice, an adjustable plate controlling the area of said inlet orifice, a vertically arranged conduit communicating with the inlet orifice of said feed conduit, a pipe supplying air to said vertical conduit, a powdered fuel hopper at the upper end of said vertical conduit, an adjustable inclined plate located below said hopper and from the lower edge of which powdered fuel is caused to fall in a continuous shower through said vertically arranged conduit and more or less closely in front of the inlet orifice of said feed conduit and means that draw regulated quantities of air and powdered fuel through said inlet orifice to said gas producer, substantially as described.

7. In apparatus for the production of combustible gas from pulverulent fuel, a gas producer comprising a long vertically arranged combustion chamber throughout the length of which jets of flame extend, and a gas and cinder collecting chamber with which the lower end of said combustion chamber communicates, a feed conduit having an inlet orifice for fuel and air to the upper end of said combustion chamber, means whereby powdered fuel is caused to pass in a continuous shower more or less closely in front of the inlet orifice of said conduit, a gas exit pipe from the said gas and cinder chamber of said producer and suction means that draw gas from said pipe and regulated quantities of air and powdered fuel through said inlet orifice and into said combustion chamber, substantially as described.

8. In apparatus for the production of combustible gas from pulverulent fuel, a gas producer comprising a long vertically arranged combustion chamber throughout the length of which jets of flame extend, and a gas and cinder collecting chamber with which the lower end of said combustion chamber communicates, a feed conduit having an inlet orifice for fuel and air to the upper end of said combustion chamber, means whereby powdered fuel is caused to pass in a continuous shower more or less closely in front of the inlet orifice of said conduit, a gas exit pipe from the said gas and cinder chamber of said producer and a motor driven by the gas de-

livered through said exit pipe and adapted to draw regulated quantities of air and powdered fuel through said inlet orifice according to the work being done, substantially as described.

9. In apparatus for the production of combustible gas from pulverulent fuel, a gas producer comprising a long vertically arranged combustion chamber throughout the length of which jets of flame extend, and a gas and cinder collecting chamber with which the lower end of said combustion chamber communicates, a feed conduit having an inlet orifice for fuel and air to the upper end of said combustion chamber, a second conduit communicating with the inlet orifice of said feed conduit, and with the atmosphere, distributing means whereby powdered fuel is caused to pass in a continuous shower through said second conduit and more or less closely in front of the inlet orifice of said feed conduit, a gas exit pipe from the said gas and cinder chamber, and a motor driven by the gas delivered through said exit pipe and adapted to draw regulated quantities of air and powdered fuel through said inlet orifice according to the work being done, substantially as described.

10. In apparatus for the production of

combustible gas from pulverulent fuel, a gas producer comprising a long vertically arranged combustion chamber throughout the length of which jets of flame extend, and a gas and cinder collecting chamber with which the lower end of said combustion chamber communicates, a feed conduit having an inlet orifice for fuel and air to the upper end of said combustion chamber, a vertically arranged conduit communicating with the inlet orifice of said feed conduit, a pipe supplying air to said vertical conduit, a powdered fuel hopper at the upper end of said vertical conduit, distributing means for causing fuel from said hopper to fall in a continuous shower through said vertically arranged conduit and more or less closely in front of the inlet orifice of said feed conduit and a motor driven by the gas delivered through said exit pipe and adapted to draw regulated quantities of air and powdered fuel through said inlet orifice according to the work being done, substantially as described.

Signed at Paris, France, this 17th day of January, 1905.
